ROOM DIVIDER

Melbourne F. Smith, Jr., Lenoir, N.C., assignor to Broyhill Furniture Factories, Lenoir, N.C., a partnership

Filed Apr. 15, 1963, Ser. No. 74,435

Term of patent 14 years

(Cl. D33—19)

The end not shown is the same in appearance as the end shown.

The dominant features of my design reside in those portions shown in full solid lines on the drawing.

I claim:

The ornamental design for a room divider, substantially as shown and described.
